ELECTRICAL JUNCTION BOX

James Wesley Hudson, Elmhurst, Ill., assignor, by mesne assignments, to The National Supply Company, a corporation of Pennsylvania

Application September 27, 1955, Serial No. 38,113

Term of patent 14 years

(Cl. D26—1)

Fig. 1

Fig. 2

Fig. 1 is a top perspective view of an electrical junction box, showing my new design; and

Fig. 2 is a top plan view thereof.

The opposite sides, not shown, have substantially the same appearance as the sides shown in Fig. 1, and the bottom is a plain flat surface.

I claim:

The ornamental design for an electrical junction box, substantially as shown and described.
